Inventor,

Charles Hugh Woodbury

UNITED STATES PATENT OFFICE.

CHARLES HUGH WOODBURY, OF LOS ANGELES, CALIFORNIA.

QUICK-DETACHABLE TIRE-VALVE DUST CAP.

1,421,117.

Specification of Letters Patent. Patented June 27, 1922.

Application filed July 18, 1919. Serial No. 311,883.

To all whom it may concern:

Be it known that I, CHARLES HUGH WOODBURY, a citizen of the United States, and a resident of Los Angeles, in the county of 5 Los Angeles and State of California, have invented a new and useful Improvement in Quick-Detachable Tire-Valve Dust Caps, of which the following is a specification.

This invention relates to tire valve dust caps and the principal object is to provide a dust cap that may be quickly removed and closely contacts with the inclined conical face of the securing nut for the valve and forms a perfect water tight and dust proof 15 cover.

A further object of the invention is to provide the cap with knurled surface for gripping the same, the cap being preferably formed out of sheet metal that will be light, 20 easy of manufacture and have sufficient elasticity to give spring action to the gripping margin.

In the drawing accompanying this specification Fig. 1 is an elevation of the cap and 25 the valve nut shown with one of the two slits to allow the lower margin to slip over the conical extension of the nut.

Fig. 2 is a plan view of the device and

Fig. 3 is a central longitudinal section of 30 the lower portion of the cap, with the nut and its truncated conical extension in elevation, the stem of the valve being shown in dotted lines.

My invention overcomes the above difficulties and forms an absolute seal to the entrance of dust or water that would tend to carry deposited dust into the chamber formed by the cap through the crevices usually found.

40 Calling attention particularly to the drawing, described above, the nut or lock usually found on a valve stem is shown as numbered 5. of the usual hexagon form, the same being formed with a conical projection 6 extending outwardly from its contact with the wheel rim and being preferably truncated, as shown, with only a slight margin 7 extending beyond the outer diameter of the threads on the stem 8.

50 The projection is also grooved or machined to have a reverse conical surface 9 which forms the contacting portion of the gripping edges 10 of the cylindrical cap 11, adapted to embrace these conical portions 55 of the nut.

The cap 11 as stated is preferably cylindrical and may be drawn or spun out of resilient metal of sufficient thickness to form a light and graceful cover, the same being split from the gripping margin upward as 60 shown in Figs. 1 and 3 at 12 to a point just below the annular groove or corrugation 14 formed in the cap, this groove being of such depth as to form a projection inwardly to contact with the conical surface 6 just before the gripping margins reach the limit of their gripping action on the surface 9, so that there is a tendency to draw the inside surface of the groove 14 to a tight fit on its opposing surface to form a complete dust 70 and water seal.

To form a good grip in removing or applying the cap the upper or outer portion of the same is preferably knurled as shown at 15, the whole being closed at the end by the 75 top 16 either formed with or secured in other well known mechanical methods.

This cap will not rattle on the nut from wear as has occurred with other devices of this character, the same being of such a simple character that anyone may compress the inturned spring margin 10, should they become stretched and fail to draw the annular projection 14 in contact with the cone, the surface 9 being preferably formed of greater 85 width than the part 10 to accommodate the slight wear that might take place, the cap seating with a snap that assures the operator that it is locked securely and properly 90 performing the required functions.

Having thus described my invention, what I claim is:

The combination with a pneumatic tire valve stem nut having a frusto conical portion projecting from the face thereof, said 95 frusto conical portion having an annular groove at the junction of the conical portion and nut, of a substantially cylindrical dust cap having an inturned lower edge for detachably engaging said annular groove, and 100 having an annular internal rib located at a distance from the said lower edge which is less than the height of the frusto conical portion whereby when said inturned edge is in engagement with the groove the internal 105 rib contacts with the surface of the frusto conical portion below the top thereof.

CHARLES HUGH WOODBURY.
